ATTORNEY

UNITED STATES PATENT OFFICE.

THOMAS HILL, OF JERSEY CITY, NEW JERSEY.

WAGON-BODY.

SPECIFICATION forming part of Letters Patent No. 634,750, dated October 10, 1899.

Application filed September 2, 1899. Serial No. 729,284. (No model.)

To all whom it may concern:

Be it known that I, THOMAS HILL, a citizen of the United States, and a resident of Jersey City, in the county of Hudson and State of New Jersey, have invented certain new and useful Improvements in Wagons, of which the following is a specification.

The invention relates to improvements in wagons, and more particularly to wagons of the character employed for collecting the refuse of cities.

My invention consists in a deep-bodied wagon having double vertically-hinged doors at its rear end and provided with detachable means for engaging the vertical meeting edges of the doors and holding the doors firmly closed.

The object of my invention is to improve the construction of the rear end of the wagon, whereby it is given great strength, with conveniences for the removal of the load; and a further object of my invention is to provide adequate, simple, and durable means for preventing the pressure of the load from bulging the rear doors outward or throwing them open.

The invention will be fully understood from the detailed description hereinafter presented, reference being had to the accompanying drawings, in which—

Figure 1 is a central vertical longitudinal section through a wagon constructed in accordance with and embodying my invention. Fig. 2 is a rear end view of the body of same. Fig. 3 is an elevation, looking at the inner side thereof, of the detachable locking-bar which in use engages the vertical meeting edges of the double doors and maintains said doors in their closed position. Fig. 4 is an edge view of same. Fig. 5 is a detached elevation of a portion of the inner side of the rear end of the wagon; and Fig. 6 is a top view of a removable transverse bar which spans the upper rear portion of the wagon-body and receives a hook provided at the upper end of the detachable locking-bar.

In the drawings, the numeral 10 denotes the wagon-body, 11 one of the wheels therefore, and 12 a portion of one of the shafts.

The body 10 is of commodious character, and at its rear end said body is formed with the permanent vertical sections 13 13, whose

outer edges conform to the inclined sides of the body 10 and whose inner edges are vertical and receive the corresponding or double doors 14 14, the latter being secured to the sections 13 13 by means of the hinges 15. The vertical sections 13 and doors 14 extend the full length of the rear end of the body 10. Said doors when closed meet at the vertical center line of said end of said body.

Directly below the doors 14 is rigidly secured a transverse beam 16, which strengthens the rear end of the body 10 and forms a sill for the doors 14. At its center the beam 16 is provided with the vertical socket 17 to receive the reduced lower end of the plate 18, secured upon the lower end of the detachable locking-bar 19, said socket 17 being substantially in line with the outer vertical face of the doors 14, and said plate 18 being preferably set into the bar 19 so as to be flush with the inner face thereof and permit said face to remain flush with the outer face of said doors 14.

The bar 19 is preferably made of wood and has the plate 18 bolted on the inner face of its lower end and the plate 20 bolted upon the inner face of its upper end, said plate 20 being also set into the bar 19 so as to be flush with the face thereof. The plate 20 is bent to extend inward over the top of the doors 14 and then downward, as at 21, to enter a socket formed in the transverse bar 22, which extends from the upper edge of one section 13 to the upper edge of the other section 13 and is removable. The doors 14 close against the bar 22, and thereupon the bar 19 is applied in position to hold the doors closed. The bar 19 is furnished with a handle 23 for convenience in removing and applying said bar.

The bar 22 is preferably formed of the wooden beam 24 and metal plate 25, the latter facing the outer vertical side of said beam 24 and at its ends being formed with the arms 26, which project downward and are adapted to enter the keepers 27, provided to receive them, said keepers 27 being secured to the inner faces of the aforesaid sections 13, and serving, in connection with the arms 26, as convenient means for detachably holding the bar 22 in position. The bar 22 not only serves as a means against which the doors 14 may

close, but also as a transverse stay-beam which strengthens the rear portion of the wagon-body, and since said bar 22 is removable it does not interfere with the removal of the load from the wagon.

In the employment of the wagon shown the doors 14 usually remain closed except when the load is to be removed, and hence in the normal condition of the wagon while in use collecting refuse the bar 22 will be in position and the doors 14 closed and held closed by means of the bar 19, whose lower plate 18 will enter the socket 17 of the lower bar 16 and whose upper plate 20 will be hooked into the socket 28 of the upper bar 22. When it is desired to remove the load from the wagon, the bar 19 is lifted from its sockets 17 and 28 and the doors 14 allowed to open. The bar 22 may at this time also be removed, and thus leave the rear end of the wagon free to permit the ready removal of the load.

When the bar 19 is in position it effectually locks the doors 14 in closed position, and said bar is of sufficient width to engage the meeting portions of both doors.

In the construction hereinbefore described I provide simple, durable, and effective means for holding the doors 14 closed and also strengthen the rear end of the wagon, the bars 16 and 22 affording strength as well as furnishing the sockets 17 and 28 for the bar 19.

What I claim as my invention, and desire to secure by Letters Patent, is—

1. In a wagon, the body 10 having the vertical hinged doors 14, and transverse bars 16 and 22, combined with the vertical detachable locking-bar 19 engaging said bars 16 and 22 and extending along the meeting portions of said doors; substantially as set forth.
2. In a wagon, the body 10 having at its rear end the sections 13, the vertical doors 14 hinged thereto, the lower bar 16 extending outward beyond the said doors, and the upper bar 22 at the inner side of said doors, 45 combined with the vertical detachable lock-

ing-bar 19 engaging said bars 16 and 22 and extending along the meeting portions of said doors; substantially as set forth.

3. In a wagon, the body 10 having at its rear end the vertical hinged doors 14, and 50 the bars 16 and 22 respectively provided with sockets 17 and 28, combined with the vertical detachable locking-bar 19 engaging said sockets and extending along the meeting portions of said doors; substantially as set forth. 55

4. In a wagon, the body 10 having at its rear end the vertical hinged doors 14, the lower bar 16 having a socket 17, and the upper bar 22 detachably held in place, combined with the vertical detachable locking-bar 19 engaging said bars 16 and 22 and extending along the meeting portions of said doors; substantially as set forth. 60

5. In a wagon the body 10 having at its rear end the sections 13, the vertical doors 14 hinged thereto, the lower bar 16, and the upper bar 22, the latter having the arms 26 to engage the keepers 27 secured to said sections 13, and said bars 16 and 22 respectively having sockets 17 and 28, combined with the vertical detachable locking-bar 19 engaging said sockets and extending along the meeting portions of said doors; substantially as set forth. 70

6. In a wagon the body 10 having at its rear end the vertical hinged doors 14, the lower or sill bar 16, and the upper inner bar 22, combined with the vertical detachable locking-bar 19 having the plate at its lower end to enter a socket in said bar 16 and provided at its upper end with the hook-shaped plate to reach over said doors and engage said bar 22; substantially as set forth. 75

Signed at New York, in the county of New York and State of New York, this 31st day of August, A. D. 1899.

THOMAS HILL.
